Inventor.

F. R. Cornwall

UNITED STATES PATENT OFFICE.

FREDERICK R. CORNWALL, OF ST. LOUIS, MISSOURI.

MONORAIL TRANSPORTATION SYSTEM.

Application filed July 14, 1922. Serial No. 574,947.

To all whom it may concern:

Be it known that I, FREDERICK R. CORNWALL, a citizen of the United States, residing at St. Louis, Missouri, have invented a certain new and useful Improvement in Monorail Transportation Systems, of which the following is a full, clear, and exact description, such as will enable others skilled in the art to which it appertains to make and use the same, reference being had to the accompanying drawings, forming part of this application.

My invention relates to monorail transportation systems of the general type described in my copending application Serial Number 537,329, filed February 17, 1922, and consists in rail suspending means and carrier construction especially adapted for freight transportation, including the shipment of logs, lumber, and unit containers of less than a carload.

One object of my invention is to reduce the cost of such a system so that it may be installed under conditions where the extent of the length of its use would not justify the investment necessary for more complicated trackway and equipment described in the above-mentioned application.

Another object of my invention is to provide a system which may be erected and handled by unskilled labor and in places where the usual monorail construction or surface line would be very expensive and perhaps impractical.

Another object of my invention is to provide equipment for transporting freight wherein each carrier is adapted to support one or more units or containers each of which forms a complete shipment independently of the other containers which may be mounted on the carrier. This adapts my present system to form a link in a transportation route in which lading containers are transported by truck, railway cars, barge, etc., without handling the lading at each transfer.

Another object of my invention is to provide a truck and carrier construction which will be simple and rugged and at the same time possess the flexibility necessary to prevent undue deterioration of the trackway and the supporting means for the latter.

In the accompanying drawings which il-

lustrate a selected embodiment of my invention,—

Figure 1 illustrates a typical installation of my invention in a district where the system is being used for transporting logs from a lumber camp to a railroad, wharf, or other shipping point.

Figure 2 is an elevation of a portion of the trackway and its supporting elements and of a carrier mounted thereon, the latter being illustrated in a manner which discloses various means of supporting the load therefrom.

Figure 3 is a cross section of a trackway and carrier.

Figure 4 is a detail of one of the lading supporting elements mounted upon the carrier.

Figures 5 and 6 are respectively side and top views of the carrier two-wheel truck.

Figures 7, 8 and 9 illustrate details of the truck construction and will be referred to later.

The track rail 1 instead of being rigidly supported by steel towers is preferably suspended from an overhead cable 2 extending longitudinally of the rail and supported in turn at intervals by transverse cables 3 which are secured to suitable supports spaced at varying distances from each other and the track. These supports may also vary in height and in construction. In Figure 1 these supports are shown as trees which, of course, are in their original location and obviously vary in spacing and size. Where the supports must be erected this construction permits the accommodation of variations in the surface contour. In some instances the utilization of pre-existing buildings or other structures is possible.

Rail 1 is pivotally suspended from cable 2 by a plurality of vertical chains, rods or cables 4, each provided with a bracket 5, channel-like in its contour, with its flanges disposed laterally or horizontally, the end of one flange being secured to a cable 4 and the end of the other flange rigidly connected to track 1. All of these brackets have their vertical portions positioned upon the same side of rail 1 for the reason hereinafter explained.

Preferably each suspending member 4 includes a turn-buckle 6 whereby the length

of the member may be varied so as to equalize the tension upon the member and provide an equal distribution of the rail supporting strains along cable 2.

5 The track is best illustrated in Figure 3 and consists preferably of a beam section which sustains the load and a rail section 7 which receives the tires of the truck wheels 8. This track is similar to the one shown in 10 my above-mentioned application, is old in the art and forms no part of my present invention.

While the car trucks may be of any desired type, a convenient two-wheel construction 15 is of the two-wheel type, detailed in Figures 5 and 6, and besides the wheels comprise two wheel pieces 9 and 10 and coiled springs 11 compressed between the wheel pieces to form a yielding load supporting structure. Each wheel piece is 20 journaled at one end upon its respective wheel, as illustrated in Figure 9, and extends diagonally upwardly and toward the other wheel until it crosses the other wheel piece, 25 from whence it extends horizontally toward the other wheel. These wheel pieces are arranged in pairs and the pair 10 journaled on one wheel are spaced from each other a greater distance than the pair 9 journaled 30 on the other wheel so that when the pieces cross each other, the outer surfaces of the latter pair are adjacent to the inner surfaces of the former pair. Where the wheel pieces cross each other they are pivotally connected 35 by a pin 12 and where the horizontal portion of one wheel piece opposes the diagonal portion of the other wheel piece, suitable spring seats 13 are provided. By this construction any depression or elevation in the 40 rail or anything else which would cause a disturbance in the strain upon one of the wheel journals is immediately equalized by the compression of one spring 11 and the expansion of the other.

45 The carrier in the present embodiment consists of a structural I-beam 14 which is supported from each of the trucks by a channel-like bracket 15, the upper end of which extends up that side of the wheel 50 pieces which is opposite from the side upon which rail supporting brackets 5 are located. The upper flange of bracket 15 extends across wheel pieces 9 and 10 and is flanged downwardly on the opposite side far enough 55 to receive pin 12 which also extends through the body of the bracket and is thereby placed in double shear. The pin 12 and bracket 15 form a pivotal mounting for the carrier 14, enabling it to swing longitudinally of the 60 track and thus relieve the latter and the trucks from excessive strains which would result from a rigid support of the carrier.

The lower portion of bracket 15 extends laterally and upwardly corresponding to the 65 extension of the upper portion of the brack-

et and the carrier 14 is provided with a ball and socket bearing 16 in this flange of the bracket so that pivotal movements in a longitudinal plane of the bracket upon the truck and pivotal movements of the carrier in a transverse plane upon the bracket 15 are readily accommodated.

Slidably mounted upon carrier 14, but provided with fastening means, is a series of hangers 17 each here shown as provided with a hook 18 adapted to engage an eye 19 of a suspended container 20, a link of a log chain 21, or any other load supporting means. These hooks 18 are preferably pivoted to hangers 17 so as to further relieve the whole system from strain, and it will be noted that the load is pivotally suspended from hooks 18, thus being further conducive to the same end.

85 Containers 20 are cubical cases suitably reinforced by structural elements 22 and provided with doors, hoppers, or other load receiving and discharging elements according to the class of merchandise for which they are intended. Each of these containers 90 may be mounted upon a carrier independent of the other and may be unshipped at any point, thus providing for uninterrupted travel of the carrier and the elimination of 95 repeated handling of the merchandise.

Where two or more containers are supported upon one carrier, it is necessary to prevent their swinging against each other and therefore each container is provided with a link 23 mounted on one edge and a link engaging element 24 mounted on its opposite edge, link 23 and element 24 on adjacent containers serving to brace them 100 from each other as shown in Figure 2.

105 It will be understood that the containers 20 may be made in various sizes for different classes of merchandise. Obviously, a container intended to carry bulky goods, such as furniture or machinery, would necessarily be larger and probably of a different 110 construction than that required for grain or ore.

Some containers might require a plurality 115 of brackets 17. Some merchandise could be suspended from the carrier without any container. The logs 25 are only one form of such merchandise. Hence the adjustability of brackets 17 along carrier 14 is a material advantage.

120 Each carrier is provided with suitable coupling elements 26 whereby a plurality of carriers may be coupled together just as the cars of a train, and it will be understood that a locomotive truck will usually be provided for motive power, although, under certain limited conditions, the system may be operated as a gravity monorail, the carriers being returned to their loading point by a cable or similar arrangement.

125 Various modifications in the details of 130

construction of my invention will suggest themselves and I contemplate all such as are included in the scope of the appended claims.

I claim:

- 5 1. In a monorail carrier, a truck comprising tandem wheels, individual wheel pieces each journaled at one end on one of said wheels, crossing each other and having a pivotal interengagement at their crossing
- 10 points, means supporting the opposite end of each wheel piece on the other wheel piece, and a load carrying member suspended from the point of interengagement of said wheel pieces.
- 15 2. In a monorail carrier, spaced trucks each comprising tandem wheels, individual wheel pieces journaled at their ends on said wheels, crossing each other and having a pivotal interengagement at their crossing point, and provided with a load carrying member pivotally suspended from the point of their interengagement, and a rigid frame carried by said members.
- 20 3. In a monorail carrier, a truck comprising tandem wheels, individual pairs of

wheel pieces each pair journaled at one end on one of said wheels, the members of one pair being spaced further from each other than the members of the other pair, said pairs crossing each other and having a pivotal interengagement at their crossing point, the vertically aligned portions of said pieces having opposed spring seats, springs compressed between said seats, and a load carrying element suspended from the pivotal interengagement of said wheel pieces. 30

4. A monorail truck whose wheels are flexibly connected for independent movement, and a suspended load, the point of reaction of said load being located within 40 the zone of the wheel base.

5. A monorail truck whose wheels are flexibly connected for independent arcuate movement, and a suspended load, the point of reaction of said load being located within 45 the zone of the wheel base.

In testimony whereof I hereunto affix my signature this fifth day of July, 1922.

FREDERICK R. CORNWALL.
